UNITED STATES PATENT OFFICE.

JAMES R. HUNTER, OF ASHEVILLE, NORTH CAROLINA.

WRENCH.

1,212,063.

Specification of Letters Patent.

Patented Jan. 9, 1917.

Application filed July 7, 1916. Serial No. 108,061.

To all whom it may concern:

Be it known that I, JAMES R. HUNTER, a citizen of the United States, residing at Asheville, in the county of Buncombe and 5 State of North Carolina, have invented certain new and useful Improvements in Wrenches; and I do hereby declare the following to be a full, clear, and exact description of the invention, such as will enable others skilled in the art to which it 10 appertains to make and use the same, reference being had to the accompanying drawings, and to the letters and figures of reference marked thereon, which form a part 15 of this specification.

This invention relates to new and useful improvements in wrenches and especially in the provision of a sliding jaw held in different adjusted positions by means of a spring- 20 pressed ratchet or pawl.

My invention comprises various details of construction, combinations and arrangements of parts which will be hereinafter fully described, shown in the accompanying 25 drawings and then specifically defined in the appended claims.

I illustrate my invention in the accompanying drawings, in which:

Figure 1 is a side elevation of a wrench 30 made in accordance with my invention. Fig. 2 is a central longitudinal sectional view. Fig. 3 is a cross sectional view on line 3—3 of Fig. 2.

Reference now being had to the details 35 of the drawings by letter, A designates a fixed jaw having a shank B, the end of which is contracted as at B' and circumferentially threaded at its end, and C is a handle fitted over said contracted end.

40 D designates a movable jaw which has a longitudinal slot therethrough to receive the shank portion of the jaw A. A resilient strip, designated by letter E, is fastened to the rear edge of the shank B and bears 45 yieldingly against the wall of the slot and serves to hold the jaw steady when being moved to different positions.

The shank portion of the movable jaw has a recess therein, designated by letter H, and 50 K is a pawl pivoted to the pin L in a slot in the sleeve J, which fits over the shank portion of the fixed jaw, and the pawl K has

its outer edge convexed and provided with teeth N, and O is a spring fastened to said handle and bearing yieldingly against the 55 pawl and adapted to throw the same normally at its farthest outer throw. Said teeth of the pawl are adapted to engage over the end wall of the recess in the shank portion of the movable jaw and to hold the 60 latter in different adjusted positions.

Upon reference to Fig. 2 of the drawings, it will be noted that a coiled spring B³ is mounted in a recess B² formed within the shank portion of the jaw B and one end 65 bears against the inner end of the recess and the other end against the pin B⁴, the purpose of which is to normally hold the jaws separated from each other.

In operation, it will be noted that, when 70 the movable jaw is moved toward the fixed jaw, the movable jaw will be automatically held in different adjusted positions by the teeth on the concaved edge of the pawl coming in contact with the end of the shank 75 portion of the movable jaw. When it is desired to return the movable jaw to its normal position, it may be done by first depressing the pawl out of the path of the wall of the recess. 80

What I claim to be new is:—

1. A wrench comprising a fixed jaw and a sliding jaw with a slot to receive the shank of the fixed jaw, the shank of the sliding jaw having a recess, a spring interposed between the shank portion of the fixed jaw and the wall of the slot, a sleeve upon the shank portion of the fixed jaw, a pawl carried thereby and adapted to engage the end of the shank portion of the movable jaw. 85 90

2. A wrench having a fixed jaw with a shank portion having a contracted end, a handle upon the latter, a sleeve upon said shank portion, a movable jaw slotted to receive the shank of the fixed jaw and having a recess in one end, a spring-pressed dog carried by said sleeve and adapted to engage over the end of the recess in the sliding jaw. 95

In testimony whereof I hereunto affix my signature in presence of two witnesses.

JAMES R. HUNTER.
